SEPARABLE FASTENER FOR FABRICS AND COVERINGS

Arthur Illsche, Rye, N. Y.

Application February 23, 1939, Serial No. 257,955

4 Claims. (Cl. 24—105)

The invention relates to fasteners for removably securing fabrics in position for use, particularly where the use is such as to make removal of the fabrics, at more or less frequent intervals, desirable or necessary.

While the invention may be readily adapted for various uses, other than above mentioned, as will be evident, it will not be necessary, for present purposes, to extend the disclosure to all such and the showing herein will accordingly be limited to a typical illustrative embodiment, suitable for general use and herein employed for removably securing covering fabrics of the class likely to be "roughed-up" or displaced in use, such as slip covers, bed covers, rugs, carpets and the like, which must be detachably held, to permit ready removal at will.

As herein embodied, the fastener is of the multiple member type, certain members of which are separably associated in engaging relation by a screw-thread connection and are adapted to be thus engaged with a fabric interposed without puncture, between them. The engaged portions of the members, which carry the screw-threads, are of frustro-conical form to accommodate fabrics of different thickness. The screw-thread does not, ordinarily, exceed two turns and engagement and disengagement are effected by rotation through less than a complete revolution, owing to the frustro-conical form given the threaded portions of the members. The taper permits free entrance of one into the other, to almost their full depth, preparatory to engagement and it then only requires a partial turn clockwise, to fully interlock the members. To prevent accidental disengagement, by being worked loose and given counterclockwise rotation by the pull or strain of the fabric, a swivel mounting is provided which enables the engaged members to rotate together, in either direction under the pull of the fabric, with such freedom, that any and all tendency of the members towards independent rotation that would eventually result in disengagement, is practically eliminated. As a check on this free rotation, such as is required when the members are to be engaged or disengaged, a stop formation is employed to cooperate with one of the members and may be brought into action at will, by pressing the members together while one is screwed into or unscrewed from the other. Upon the pressure being removed, the stop is automatically disengaged, preferably by spring action, and the member with which it cooperates, is released for free rotation in either direction.

Other features of the invention not specially mentioned above, will be brought to attention, in the detail description that follows.

In the accompanying drawings I have illustrated a practical embodiment of the invention and a slight modification but point out with reference to the constructions shown, that no limitations upon the invention are intended other than are imposed by the scope of the appended claims.

In the drawings—

Fig. 1 is a central vertical sectional view, showing the fastener and the manner in which it is employed to removably secure a covering fabric in position for use.

Fig. 2 is a similar view, showing the stop 15 brought into action by pressure on the upper fastener member checking rotation of the lower fastener member, to permit independent rotation of the upper member, as required for either engagement or disengagement thereof.

Fig. 3 is an exploded view of the Fig. 1 assembly.

Fig. 4 is a detail view in plan of the upper side of the female fastener member.

Fig. 5 is a like view of the upper side of the base plate of the swivel mounting.

Fig. 6 is a fragmentary sectional view, on a much enlarged scale, showing the detail construction of the swivel mounting and the stop formation.

Fig. 7 illustrates a slightly modified form of the swivel mounting and stop formation, the base plate and female member being shown in perspective in separated relation, and

Fig. 8 is a fragmentary sectional view, showing the base plate and female member assembled.

Referring now to the drawings, the fastener shown, consists of a male member 1 and a female member 2, both of which are preferably shaped up from sheet metal but may be molded or otherwise formed, if desired.

Centrally of the disk body 3, of each member, a frustro-conical projection 4 is formed. These projections are relatively proportioned to fit one within the other in nested relation, as shown in Figs. 1 and 2.

The frustro-conical projections of the members are screw-threaded, as indicated at 5, for interlocking engagement. The thread is of coarse pitch and preferably of the ratchet type. Ordinarily, it does not exceed two turns in length but may be extended if desired. Constructed as described, one member enters freely into the other to nearly its full depth, preparatory to interlocking, and upon giving the male member 55

about half a turn clockwise, complete interlocking engagement of the members is effected.

The fastener members are designed to enter into engagement one with the other through the fabric 6 to be secured by them. The fabric is interposed without puncture between the members and may be a slip cover, bed cover, rug, carpet or the like, to the different thicknesses of which the fastener adapts itself by the self-adjusting action of the frusto-conical engaging portions of the members.

To prevent accidental disengagement of the fastener members by reverse or counterclockwise rotation, resulting from the pull, tug or strain of the fabric, a swivel mounting is provided for the female member, which permits free rotation thereof in either direction, enabling the female member to turn with and follow the movement of the male member and in thus checking independent rotation of either member, accidental disengagement is avoided.

The swivel mounting consists of a base plate 1, designed to be let in flush and secured fast, by screws or otherwise, to the frame of a chair 25 or bed or a floor, as indicated at 1^a, in Figs. 1 and 2. The base 1 may be in the form of a disk, a square or rectangular plate or given any other shape preferred. It is depressed centrally at 8, as shown in Figs. 1 to 3, inclusive and Fig. 5, or 30 may be provided with a central opening 8^a, as in Figs. 7 and 8, to accommodate the frusto-conical threaded portion of the female member 2, as shown in Figs. 1 and 2. This member is swiveled to the base plate by hooklike projections 9, from 35 the plate, entering an annular groove 10, formed by the turned-under peripheral edge 10^a, of the member.

In the form of the fastener shown in Figs. 1 to 6, inclusive, the female member is yieldingly held spaced slightly away from the base plate by spring tongues 11, formed by partial cut-outs from the plate, to permit limited axial movement of the member towards the base plate, against the action of the spring tongues 11. This axial 45 movement of the female member towards the base plate, which is imparted to it by pressure on the male member, causes the hooklike projections 9 of the base plate, to enter openings 12, formed directly above them in the member 2, as shown in Fig. 2, and serves to hold the member 2 against rotation in either direction, while the male member is rotated to engage or disengage the same. Discontinuing the pressure upon the male member, permits the springs to 55 act and move the female member upward far enough to withdraw the stop hooks 9, of the base plate from the openings 12 in the member, thereby releasing the same for free rotation.

In the modification shown in Figs. 7 and 8, 60 the springs for yieldingly holding the female member separated from the base plate, are omitted, as the pull or strain of the fabric will tend

to maintain these parts in the required relation for free rotation of the member.

The central depression of the base plate is also omitted and a through opening 8^a substituted to accommodate the frusto-conical projection of the female member, which is housed in a recess formed in the frame of a chair, bed or floor, as shown in Fig. 8.

The edge portion of the opening 8^a is bent up and turned over, forming an annular flange 8^b, 10 which has radially disposed ribs or corrugations 8^c, formed therein, designed to cooperate with corresponding ribs or corrugations 12^a of the female member, to hold the latter against rotation, when pressure is applied to the male member to engage or disengage the same, as above described. The annular flange 8^b of the base plate projects into the annular peripheral groove of the female member to form the swivel connection between the member and the plate, as above described and, excepting the differences mentioned, the two constructions are substantially similar.

As the many important advantages of the fastener will be apparent from the foregoing description, it will not be necessary to list and elaborate the same beyond pointing out the ready adaptability of the device, without material change or modification, to serve many purposes other than herein mentioned.

Having described my invention, I claim:

1. A fastener comprising three associated members including an upper member, a lower member and an intermediate member, the intermediate member and the lower member being permanently connected in selected swiveling relation to define a swiveling unit, said upper member and said intermediate member having complementary screw-threaded engaging means for releasably securing a fabric therebetween, means in the swiveling unit to maintain its members in swiveling relation and stop means also located in said unit to selectively prevent swiveling of the members whereby a fabric may be secured between the upper and intermediate members or released therefrom by a relative rotation thereof.

2. A fastener as defined in claim 1, in which the fastener members are provided with engaging portions of frusto-conical form to accommodate fabrics of different thickness interposed without puncture between them.

3. A fastener as defined in claim 1, in which the stop means are normally held disengaged by spring tongues integral with and struck up from the lower member of the fastener.

4. A fastener as defined in claim 1, in which the stop means consists of co-operating elements, normally held disengaged by springs and engageable against the action of the springs by axial movement of the intermediate fastener member.

ARTHUR ILLSCHE.
